UNITED STATES PATENT OFFICE.

JAMES S. THOMPSON, OF NEW YORK, N. Y., ASSIGNOR TO AMERICAN BRAKE MATERIALS CORPORATION, OF NEW YORK, N. Y., A CORPORATION OF NEW YORK.

FRICTION BRAKE.

Application filed September 24, 1926. Serial No. 137,425.

This invention relates to shoes for friction brakes and more particularly to that type of shoe which comprises a composition body mounted on a metal back.

5 The object of the invention is to provide an efficient shoe for a friction brake and having its body secured to the metal back in a novel manner which will endure throughout the life of the shoe in service.

10 Another object of the invention is to provide novel means for securing the body to the back of the shoe which will maintain the shape of the body and prevent undesired weaknesses from developing in the body in 15 the manufacture and actual service of the shoe.

And a further object of the invention is to embed the body in a back having the form 20 of a shell and to prevent the body from buckling or springing away from contact with the back of the shell by securing the body to the shell in an efficient manner and thereby maintain the body in a desired size and shape with a uniform wearing surface.

25 And a still further object of the invention is to provide special means for securing the body to the back at or about the middle of the shoe and which means will not project beyond the general plane of the back of the 30 shoe.

In the accompanying drawings I have illustrated the invention in a selected embodiment which I have found satisfactory in practical use and referring thereto

35 Fig. 1 is a side elevation of the shoe partly broken away and in section;

Fig. 2 is a back plan view of the shoe;

Fig. 3 is an end view and

40 Fig. 4 is a transverse sectional view on the line 4—4 of Fig. 1.

The body 5 of the shoe is made of a suitable composition which will provide friction sufficient for the intended purpose and which is wear and heat resistant. I do not claim 45 the composition in this application because this invention is not restricted to the use of a particular composition but is capable of use with a body formed of any composition suitable for the intended purpose. Therefore 50 I do not restrict myself in this application to the use of any particular composition so long as it is capable of producing satisfactory results.

The shoe is concavo-convex in form and it 55 is provided with a metal back which is made

fast to the concave back of the body. I have found it convenient and satisfactory to make this back in the form of a hollow shell 6 which is perforated to receive portions of the body composition for securing the body 60 to the shell. Some of these perforations 7 are located in the side edges of the shell where the flange 8 joins the back 9, the perforations being partly in the flange and partly in the back. Other perforations 10 are provided in 65 any suitable size, number and arrangement in the back of the shell. In the commercial embodiment of this invention I have found it convenient to provide two rows of these perforations 10, as shown in Fig. 2. A panel 11 70 centrally disposed between the sides of the shell and extending lengthwise thereof is offset to form on the back of the shell a shallow channel, and this channeled portion of the back of the shell is provided with a plurality 75 of perforations 12 to receive the body material. That portion of the back of the shell having the perforations 12 is channeled so that the composition body material may project through the perforations 12 and spread 80 out in the form of a button 13 around the edges of the perforations to anchor the body to the shell firmly and securely, without projecting beyond the general plane of the back of the shell.

It has been discovered that in the manufacture of composition friction shoes there is a tendency at times for the back to bulge forwardly so that the convex wearing face of the body will be curved or bulged transversely or longitudinally or both. This does not appear in all shoes and it is generally not to an objectionable degree in those shoes in which it appears but it is desirable, of course, to produce a standard shoe at all times and I have found that this can be assured by providing an efficient anchor between the body and the shell through the middle of the shoe. It will be understood that the body composition embeds itself in the perforations 7 and 10, and this embedding affords a certain degree of anchorage which is often sufficient if the perforations 10 are distributed over the back of the shoe; but, as I have said, sometimes the body bulges between its sides and ends and it is to avoid the possibility of this that I have provided the more staple anchorage which is afforded by the buttons 13 clinching upon the back. This is a simple construction, it does not add 105 110

materially, if at all, to the cost of manufacture and it prevents the central portion of the shoe from bulging or bridging on the back, and it insures permanency of interlocking engagement between the body and the back throughout the process of manufacture and actual service of the shoe.

5 Provision may be made for fastening the shoe to a support and for this purpose sections 14 of the ends of the shell may be cut and turned down inwardly upon the back of the shell to provide a double thickness of metal at the bottom of recesses 15 formed in the ends of the body.

10 15 I have found it convenient and desirable to provide a metal back in the form of a shell but this may not be necessary in all embodiments of the invention and since it is not essential I do not restrict the invention there-
20 to but may make the back in the form of a plate without sides or ends in any form that may be found satisfactory; and I also reserve the right to make any other changes that may be found desirable within the scope of the
25 following claims.

I claim:

1. A friction brake shoe comprising a composition body and a metal back thereon, said back having a channel formed therein and
30 provided with perforations, parts of the body extending through said perforations and into said channel to anchor the body to the back.

2. A friction brake shoe comprising a composition body and a metal back thereon, said back having a channel formed therein and provided with spaced perforations, parts of the body extending through said perforations and spread out on the back around the
40 edges of the perforations to anchor the body to the back.

3. A friction brake shoe comprising a composition body and a metal back thereon, said back having a longitudinal channel formed therein and provided with spaced perforations, parts of the body extending through said perforations to anchor the body to the back.

4. A friction brake shoe comprising a composition body and a metal back thereon, said back having a longitudinal channel formed therein midway between the sides of the back and provided with a row of spaced perforations extending lengthwise of the channel, parts of the body extending through said perforations to anchor the body to the back.

5. A friction brake shoe comprising a composition body and a metal back thereon, said back having a depression therein and said depressed part being provided with perforations, parts of the body extending through said perforations and forming buttons within the depression to anchor the body to the back.

6. A friction brake shoe comprising a composition body and a metal back thereon, said back being bent on substantially parallel lines extending longitudinally of the back to form an inwardly depressed channel, and said channel portion of the back being perforated to receive portions of the composition.

7. A friction brake shoe comprising a composition body and a metal back thereon, said back being bent on substantially parallel lines extending longitudinally of the back to form an inwardly depressed channel, and said channel portion of the back being perforated to receive portions of the composition, said portions being spread to overlap the edges of the perforations and forming but-
80 tons within the channel.

JAMES S. THOMPSON.
